UNITED STATES PATENT OFFICE

168,110

FLEXIBLE BOTTLE

Jules Montenier, Chicago, Ill.

Application June 14, 1950, Serial No. 10,510

Term of patent 14 years

(Cl. D58—6)

To all whom it may concern:

Be it known that I, Jules Montenier, a citizen of the United States, residing at Chicago, in the county of Cook and State of Illinois, have invented a new, original, and ornamental Design for a Flexible Bottle, of which the following is a specification, reference being had to the accompanying drawing, forming a part thereof.

In the drawing:

Fig. 1 is a front elevational view of a flexible bottle showing my new design;

Fig. 2 is a side elevational view thereof; and

Fig. 3 is a top plan view thereof.

The dominant feature of my design resides in the portions shown in full lines.

I claim:

The ornamental design for a flexible bottle as shown and described.

JULES MONTENIER.
